Primary Examiner — Derrick E Holland*Assistant Examiner* — Jennifer O King(74) *Attorney, Agent, or Firm* — Sullivan & Worcester LLP(57) **CLAIM**

I claim the ornamental design for a cable clip, as shown and described.

DESCRIPTION

FIG. 1 is a front perspective view of a cable clip shown in an open position according to my new design.

FIG. 2 is a front view thereof, the front and rear view being identical;

FIG. 3 is a right side view thereof, the left side view being identical;

FIG. 4 is a top view thereof;

FIG. 5 is a bottom view thereof; and

FIG. 6 is a perspective view thereof, shown in use.

FIG. 7 is a front perspective view of the cable clip of FIG. 1 shown in a closed position;

FIG. 8 is a front view thereof, the front and rear view being identical;

FIG. 9 is a right side view thereof, the left side view being identical;

FIG. 10 is a bottom view thereof; and,

FIG. 11 is a perspective view thereof, shown in use.

The broken lines shown in FIGS. 5 and 10 show portions of the cable clip that form no part of the claimed design. The broken lines shown in FIGS. 6 and 11 show environmental structure and form no part of the claimed design.
